UNITED STATES PATENT OFFICE.

BENJAMIN W. CONAWAY, OF BRIDGEVILLE, DELAWARE.

LOCK.

1,126,709.

Specification of Letters Patent.

Patented Feb. 2, 1915.

Application filed February 17, 1914. Serial No. 819,260.

To all whom it may concern.

Be it known that I, BENJAMIN W. CONAWAY, a citizen of the United States, residing at Bridgeville, in the county of Sussex and State of Delaware, have invented new and useful Improvements in Locks, of which the following is a specification.

This invention relates to locks and more particularly to coin-controlled locks.

The invention is associated with lockers, private compartments and the like and has for its object the provision of novel and efficient means for releasing the lock so that access may be had to the compartment or locker upon the insertion of a coin of the proper denomination.

A further object of the invention is the provision of a device of this character in which a coin, check or other similar article automatically places in operation suitable mechanism for unlocking the lock whereby access may be had to the compartment or locker for automatically disconnecting the lock opening mechanism from the lock and for delivering a key to the depositor of the coin which gives him access to the lock while in possession of the same and another object is to construct the lock in such manner that upon insertion of the delivering key and the retraction of the bolt thereby said key will be locked against removal.

A further object of the invention is the provision of novel means actuated upon release of the lock to indicate the condition of the compartment or locker whether occupied or not.

Another object of the invention is the provision of novel means for preventing the actuation of the machine by spurious coins or by coins of a denomination not adapted to the actuation of the machine, such as coins of larger or smaller denominations, particularly the latter.

A further object of the invention is the provision of novel means for holding the release lever in operated position during the movement of the key discharging carriage.

Further objects of the invention will appear as the following description is read in connection with the accompanying drawing, which forms a part of this application, and in which:

Figure 1 is a front elevation of the lock. Fig. 2 is an inside elevation of the locker door showing the mechanism thereon. Fig. 3 is an edge elevation. Fig. 4 is a top plan

view. Fig. 5 is a vertical sectional view taken on the line 5-5 of Fig. 3. Fig. 6 is a vertical sectional view on the line 6-6 of Fig. 2. Fig. 7 is a detail vertical sectional view on the line 7-7 of Fig. 2. Fig. 8 is a detail vertical sectional view on the line 8-8 of Fig. 2. Fig. 9 is an elevation of the lock removed from the door. Fig. 10 is a detail vertical sectional view through the door showing a manner of holding the signal. Fig. 11 is a detail front elevation of the locker with parts broken away to show the mechanism for actuating the automatic release lever.

Referring more particularly to the drawing, 1 represents a locker door which is connected to the locker 2 by spring hinges 3 arranged to throw the door to open position when the bolt 4 is released, as will be hereinafter described. The bolt 4 forms part of a lock 5 having two key cylinders 6 and 7, the former constructed with a cam shaped collar 8 having a shoulder 9 thereon arranged to be engaged by the pawl 10. This pawl is spring pressed into engagement with the collar 8 at all times and the shoulder 9 is so arranged that when the bolt is retracted by a key turned in the key cylinder 8 the pawl will engage the shoulder when the bolt is in fully retracted position. The first key cylinder 7 has secured thereto an arm 11 adapted to be moved against the pawl for releasing it from the shoulder 9.

The rear end of the bolt 4 is provided with a hook 12 which projects through the casing of the lock 5 and is arranged to be engaged by the loop 13 on the end of the connecting rod 14 whose opposite end is pivotally connected to the carriage piston 15. This carriage piston is pivotally connected intermediate its ends to a crank 16 secured to the second arbor 17 of a spring clock mechanism 18. This clock mechanism is secured to the rear of the door and is inclosed within a casing 19 through which the arbor 17 passes. The casing serves to support a key delivery platform 20 in which is slidably mounted the key discharge carriage 21. This carriage is movable over the platform 20 so as to discharge a key for the cylinder 6 into a chute 22 leading through an opening 23 in the door to a receiving cup 24 on the front thereof.

Pivoted on the top of the casing 18 is a coin controlled lever 25 having a weight 26 secured to one end and a plunger 27 pivoted

thereto adjacent the same end which is normally held in the path of the escapement fan 28 of the clock work mechanism. The opposite end of the lever is provided with a downward offset upon which is secured a coin-receiving channel piece 29 which forms with the offset a recess 30 arranged to receive the controlling arm 31 carried upon and movable with the key delivery carriage 21. The delivery carriage also carries a retaining plate 32 which holds the coin in the channel member until the carriage has moved a sufficient distance to carry the arm 31 over the top of the channel member which during the movement of the carriage holds the same depressed and the plunger 27 elevated out of the path of the escapement fan.

Secured to the front of the door is a slotted plate 33 which communicates with a chute 34 which is arranged as shown to discharge into the coin receiving channel member. The chute 34 is provided with a slot 35 and opposite the slot is arranged an inwardly projecting rib 36 arranged to discharge coins of smaller denomination than those required to operate the machine, through the slot 35 into a trough 37 which communicates with the chute 38 arranged to discharge into the chute 22. Spurious coins having magnetic properties will be retained in the chute 34 by the magnet 39 over the poles of which the coins have to pass. The coins discharged from the coin receiving channel member are received in a chute 40 which conducts them to a coin receptacle 41 having a locked lid so that the box is only accessible to authorized persons.

In order that the connecting rod may be automatically disconnected from the hook 12 there is pivoted to the casing 18 a trip lever 42 arranged to engage beneath the rod 14 so as to lift it from the hook after the bolt 4 has been released and the door partially opened by the spring hinges 3. The tripping rod 42 is also arranged beneath the weighted dog 43 pivoted to a bracket 44 and arranged to engage the lower end of a signal arm 45 which is pivoted to the inner side of the door and normally drawn toward the stop 46 by a spring 47. The upper end of the arm 45 carries a segment 48 with the words "Open" and "Closed" thereon, or other similar indicia which is visible through the glazed opening 50.

In the operation of the device the parts are set, as shown in Fig. 2, with the door in closed position. The person desiring to use the locker inserts a coin of the proper denomination in the slotted plate 33. The coin passing down the chute is discharged into the coin receiving channel member and over-balancing the lever 25 it releases the plunger 27 from the escapement fan of the clock mechanism 18. As the shaft 17 rotates the carriage 21 is moved rearwardly

on the platform 20, discharging the key therefrom into the chute 22 which delivers it to the cup 24. The coin is held in the channel member by the plate 32 until the carriage has moved a sufficient distance to carry the arm 31 over the top of the channel member. This arm holds the plunger in raised position during the forward and rearward movement of the carriage, it being understood that the movement of the carriage is stopped when the arm 31 passes off the top of the channel member into the recess to the left of the same. The weight 26 then raises the channel member and depresses the plunger into the path of the escapement fan. At a time when the carriage is at its maximum outward movement and the bolt 4 in fully retracted position the tripping lever 42 is brought up beneath the rod 14 by a cam 51 secured upon the second arbor 17 so that the connecting rod is released from the hook 12 and the bolt permitted to spring outward. Simultaneously with this action the tripping lever raises the weighted end of the dog, thus disconnecting its inner end from the signal arm and permitting the spring 47 to draw said arm over against the stop. The segment will then show the word "Closed" through the opening.

After the depositor of the coin has placed his clothes in the locker the door is closed, the spring bolt locking it in closed position. To gain access to the locker the holder of the key previously deposited in the cup 24 inserts the key in the cylinder 6 and returns the same to retract the bolt. When the bolt is in fully retracted position the pawl 10 will be thrown into engagement with the shoulder 9 so that it is impossible to withdraw the key from the cylinder until the pawl is released. This is done by the person in charge of the lockers who is provided with a key arranged to fit the cylinder 7 which, upon being turned, will bring the arm 11 into contact with the pawl and throw the latter out of engagement with the shoulder 9. The spring which projects the bolt will then turn the cylinder so that it is possible to withdraw the key whereby it may be again placed upon the platform 20 for discharge by the carriage 21. When this is done the person in charge of the lockers also places the loop of the connecting rod on the hook 12 and sets the signal.

It will be noticed that coins of small size in passing the slot 35 will be projected through the same by the rib 36 and will fall into the trough 37, eventually being discharged into the cup 24. Coins of equal size with the coins of proper denominations for operation of the machine but of spurious character, such as steel or iron slugs, will be held within the chute 34 by the magnet.

It will be noticed that by disconnecting

the lock from the operating mechanism that a second person depositing a coin of the proper denomination cannot gain access to the locker and by locking the bolt operating 5 key within the lock the continuous use of said key is prohibited.

What is claimed is:—

1. The combination with a door and means normally tending to open the same, of a key operated spring projected bolt for locking the door, coin controlled means for retracting the bolt, means for disconnecting the retracting means from the bolt when the bolt is fully retracted and operable by the retracting means and means operable by the retracting means for discharging through the door a key adapted to operate the lock.
2. The combination with a door and means normally tending to open the same, of a key operated spring projected bolt for locking the door, means for retracting the bolt, coin controlled means for holding the retracting means in inoperative position, means operable by the retracting means for retaining the holding means in inoperative position while the bolt is being retracted and means operable by the retracting means for disconnecting the same from the bolt.
3. The combination with a door and means normally tending to open the same, of a key operated bolt for locking the door, means for retracting the bolt, means for discharging the key for operating the bolt and operable by the retracting means, coin controlled means for holding the retracting means in inoperative position, means operable by the key discharging means for retaining the holding means inoperative while the bolt is being retracted and operable by the key discharging means.
4. The combination with a door and means normally tending to open the same, of a spring projected bolt for locking the door in closed position, means for retracting the bolt, coin controlled means for holding the retracting means in inoperative position, means operable by the retracting means for discharging a key adapted to operate the

bolt, and means carried by the key discharging means for retaining the holding means 50 in inoperative position during the operation of the retracting means.

5. The combination with a door and means normally tending to open the same, of a key operated spring projected bolt for locking 55 the door, means for retracting the bolt, a key discharging device controlled by the retracting means, means for normally holding the retracting means inoperative and adapted to be released by a coin, means carried by the key discharging device for retaining the coin during partial retraction of the bolt and further means on the key discharging device for retaining the holding means inoperative when the coin is released, means actuated by the retracting means for disconnecting said retracting means from the bolt upon discharge of the key, and means for restoring the holding means to operative position when released 60 by the last mentioned means on the key discharging device, so as to render the retracting means inoperative.

6. The combination with a door and means normally tending to open the same, of a 75 spring actuated bolt for locking the door, coin controlled means for retracting the bolt, a signal, means for actuating the same, means for holding the signal against operation, and means for simultaneously releasing the signal holding means and the retracting means from the bolt when the bolt is operated.

7. The combination with a door and means normally tending to open the same, of a 85 spring actuated securing bolt for locking the door, coin controlled means for retracting the bolt and means operable by the reTRACTING means for releasing the latter from the bolt when the bolt is fully retracted. 90

In testimony whereof I affix my signature in presence of two witnesses.
